UNITED STATES PATENT OFFICE.

JOSEPH K. UPHAM, OF NEW YORK, N. Y.

HAT-SWEAT.

SPECIFICATION forming part of Letters Patent No. 341,616, dated May 11, 1886.

Application filed April 3, 1886. Serial No. 197,711. (No model.)

To all whom it may concern:

Be it known that J. JOSEPH K. UPHAM, a citizen of the United States, residing at New York city, in the county of New York, State 5 of New York, have invented certain new and useful Improvements in Hat-Sweats, of which the following is a specification, reference being had therein to the accompanying drawings.

My invention relates to improvements in 10 sweat-bands for hats and caps; and the objects of my improvements are to render the hat-sweat adjustable in length and diameter and permit the hats provided therewith to be fitted in an instant to different-sized heads. I 15 attain these objects by the construction illustrated in the accompanying drawings, in which—

Figure 1 is a side view of a hat-sweat constructed in accordance with my invention, a 20 portion of the outer sweat and water-proof rim being broken away and removed to show the adjustable metallic band and the clasps uniting its ends. Fig. 2 is a vertical section of the rear portion of the same hat-sweat, on a 25 larger scale, showing the elastic gore uniting the ends of the sweat-band. Fig. 3 is a side view of a portion of the sweat-band and of the metallic band with modified fastenings uniting them. Fig. 4 is a top view of the metallic adjustable band. Figs. 5, 6, and 7 show 30 modified forms of metal bands and the modes of uniting them.

Similar letters refer to similar parts throughout the several views.

The sweat-band A is made of leather, or of 35 any other suitable material, and has its ends united by means of a gore of elastic webbing, B, containing threads of india-rubber laid in horizontal rows one above the other.

To give to the sweat-band the proper length, and give thereto the necessary support to fit 40 different-sized heads, there is connected to the sweat-band by suitable means a narrow band, C, preferably of sheet metal, having its ends united by a suitable clasp that has sufficient 45 frictional adhesion therewith to retain the ends of the band C connected in any position that they may be set relatively to each other. For the purpose of uniting the ends, I prefer 50 to have them overlap each other and united by one or more clasps, D, formed of short strips of sheet metal passed across and made

to encircle the two ends of the band C, as shown in Figs. 1 and 4, the ends of the clasping-bands D being either soldered together or 55 compressed to produce the necessary friction upon the band C; but other well-known clasps may be used for the same purpose.

To increase the permanency of the adjustment of the ends of the band C, said band 60 may be crimped, as shown at e in Fig. 5, and the corrugation become interlocked under the pressure of the adjoining clasp D. Protuberances of various forms may also be formed upon one end of the band C, to enter corresponding depressions made in another portion of said band. Perforations e² may also be made in one end of the band C and the opposite end reduced in width and passed through them, as 65 shown in Fig. 6; and many other means may 70 be used to produce the desired adhesion of the ends of the band C.

Although I prefer a flat metal band, C, as above stated, it may also be made of wire, as shown in Fig. 7, or of wood, leather, or of 75 textile substance suitably stiffened at the clamped ends.

To connect the band C with the sweat-band A, various means may be used; but I prefer to use a supplementary sweat-band, A², about 80 half the width of the band A, as shown in Figs. 1 and 2. This band A² is preferably cemented (but may be stitched) to the lower edge of the band A, the line of cementation a being for about one-eighth to one-fourth inch 85 wide. In the upper portion of the band A² vertical slits a² are made, through which the band C is passed in and out, as shown, and the ends are united by the clasps or other frictional surfaces, above described. By these 90 means the band C is hidden behind the sweat-band A and does not mar its surface.

Other means may be used to secure the band C to the sweat-band—as, for example, short vertical straps a³, or cords a⁴, as shown in Fig. 95 3; but I prefer to use the continuous supplementary band A². (Shown in Figs. 1 and 2.)

The elastic webbing B, uniting the ends of the band A, permits the latter to be stretched or shortened without danger of straining or 100 tearing it while expanding the adjustable band C, or of wrinkling it while reducing the length of said adjustable band.

To the outer side of the supplementary band

A^2 and sweat-band A, adjoining their lower edge, is secured, as usual, by stitches, the doubled oil-silk band A', containing the reed a'.

I am aware that elastic cords passed through 5 eyelets have been used to connect the ends of a sweat-band, and do not claim this construction.

Having now fully described my invention, I claim—

10 1. In combination with a substantially unyielding sweat-band, a gore of elastic webbing having its upper edge longer than its lower edge, and stitched to the ends of said sweat-band to unite them, substantially as and for 15 the purpose described.

2. In combination with a sweat-band, A, and a supplementary sweat-band, A^2 , an adjustable band, C, secured to the latter and having its ends passing by each other and 20 connected, substantially as and for the purpose described.

3. The combination of a sweat-band and an adjustable band, C, surrounding the sweat-band and having its ends connected by positive means, as set forth, with means for securing said band C to the sweat-band, substantially as described. 25

4. The combination of a sweat-band, A, having its ends united by elastic webbing, with a supplementary sweat-band, A^2 , and an adjustable band, C, having its ends clasped together and secured to said band A^2 , substantially as described. 30

In testimony whereof I affix my signature in presence of two witnesses.

JOSEPH K. UPHAM.
